UNITED STATES PATENT OFFICE

WILLIAM H. LEFFINGWELL, OF WESTFIELD, NEW JERSEY

CHAIR

Application filed November 10, 1927. Serial No. 232,215.

This invention relates to an improved design in the art of chair building and particularly those types of chairs adapted for the use in schools, offices and factories, etc., 5 wherein sedentary occupations are required.

It has long been known that incorrect seating positions cause numerous internal ailments, such as indigestion, constipation, improper circulation of the blood and certain 10 nerve diseases caused by undue pressure on the nerves. Also improper breathing action may be caused by a cramped position of the lungs, together with the usual fatigue one experiences after remaining seated for a few 15 hours.

Heretofore a number of attempts have been made to correct this trouble by shaping chairs to conform to the anatomy of the body; none of which was entirely successful, due to the 20 fact that no two people or groups of people are exactly alike, and consequently a chair made to fit one or a group of persons will not be anatomically correct for another person of a different build.

25 One of the chief causes of internal body ailments is the fact that the ordinary straight back chair is uncomfortable to sit on and, in order to ease his position somewhat, the user unwittingly slides forward, thus casting the weight of his body on the lower part of the spine instead of on the lower part of the pelvis. In this position, the spine, instead of 30 being erect and straight, assumes a curved position cramping the organs of the abdomen, and the lungs, and eventually resulting in the body ailments hereinbefore mentioned.

Also these incorrect sitting postures interfere with proper circulation of the blood, and thereby induce a fatigue, which is in no respect due to the work done, whether its character be mental or manual.

An object of my invention is to provide a chair for the office worker, typist, telephone operator, etc., that will prevent the body 45 from slipping forward and hold it in erect upright position, thereby allowing the organs of the body to function in their normal manner. Another object of my invention is to so shape the seat of the chair that the weight 50 of the trunk is more evenly distributed be-

tween the buttocks and thighs thus avoiding any pressure on the under side of the knees.

In the ordinary chair the seat is made of such a depth that the user, in endeavoring to sit with his back against the back of the 55 chair, creates a pressure on the nerves and blood vessels in the popliteal region. As the veins and nerves in this region (under the knee) are very near the surface any pressure of whatever degree makes for a retarded action, sometimes causing sciatica, neuritis and a slowing up of the circulation.

Another object of my invention is to provide a chair with a seat of just sufficient depth to enable the user to sit comfortably without 60 producing a binding effect under the knee.

One of the causes of the body fatigue experienced by those in sedentary occupations is that either no back rest is provided at all or the one provided is practically useless, doing 65 more harm than good. In cases where there is a back rest it is oftentimes too high or too low and no means is provided for adjusting it to suit the back of the user. Attempts have been made, usually by inexperienced 70 workers, to provide a back rest of a shape to fit the body without first making a scientific study to ascertain the shape, position and requirements of the human body.

75 These attempts have been successful only 80 in a small degree for the reasons heretofore stated. Another object of my invention is to construct a chair with a scientifically designed and positioned back support and one that may be readily and conveniently adjusted 85 ed by the user while seated.

A deeply curved shoulder rest also has the disadvantage of crowding the shoulders forward, causing a collapsed condition of the chest and therefore another object of my invention is to provide a shoulder support for a chair which will tend to flatten the scapulae on the back and provide the necessary room for the proper functioning of the 90 lungs.

95 From the foregoing it will be apparent that nearly all, if not entirely all, of the undesirable features of the ordinary chair have been eliminated in my design for a chair disclosed herein. As a further object of my in- 100

vention, I propose to make a chair in which the user may relax completely without falling into a slumped or other improper detrimental position.

To accomplish these and other objects of my invention, I provide a chair with a shorter seat than is customarily provided and one that is shaped to comfortably fit the body in the seated position. The front edge of the seat is recessed the proper amount required to give freedom to the movement of the legs and without interfering with the circulatory or nervous systems. The rear portion of the seat is sufficiently recessed to give the correct posture position and also to maintain the body in a normal healthy erect position. To support the back and shoulders, I provide cross pieces mounted on upright supports located at the rear part of the seat; each upright support being so designed as to offer no obstruction to the arms or body. The shoulder support is curved slightly to fit the body, without crowding or cramping the lungs; while the back support for the "lumbar region" is curved slightly in two directions to more accurately conform to the contour of the occupant's back. One of the important features of this invention is the mounting and functions of this back support. To overcome the disadvantages of prior devices having a fixed support for the lumbar region, I propose to mount the support in a vertically adjustable manner and allow it to swing slightly about a horizontal axis. Thus, it will be seen that a chair incorporating this adjustable feature may be readily adapted to fit the back of any person using it.

Other objects and advantages will be in part indicated in the following descriptions and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a front elevational view of a chair embodying my invention. Fig. 2 is a side elevation thereof showing, in dotted lines, a central vertical section through the shoulder and back support to more clearly illustrate their shape and relative positions. Fig. 3 is a plan view of the chair seat and back supporting members showing their relative positions, one above the other and their curves. Figs. 4, 5, 6, 7, 8, and 9 are sectional views along lines 4-4, 5-5, 6-6, 7-7, 8-8, and 9-9, respectively of Fig. 3 showing more clearly the degree of recessing given to the seat member. Fig. 10 is a fragmentary ver-

tical sectional view through the back supporting members showing the shapes of their respective forward faces and the vertically adjustable swiveled mounting for the back support. Fig. 11 is a fragmentary front view of the chair back with parts thereof broken away to show more clearly the mounting of the lumbar rest. Fig. 12 is a section through line 12-12 of Fig. 11, showing the notched plate for retaining the lumbar rest in position.

Referring more particularly to Figs. 1 and 2 this invention is disclosed as incorporated in a chair having a well known type of standard and, as this invention relates only to that part of a chair from the seat up, it is to be understood that any type or style of standard may be used; the type shown in the drawings is for convenience of illustration only. The posture chair proper combines a deeply recessed seat member 1, with two upright supports 2, which are scientifically shaped to more closely conform to the body and designed so as to be free of any obstructions to the arms or buttocks.

Referring to Figs. 2 to 9 inclusive, it will be noted that the design of the seat member 1 presents a radical departure from the usual type of chair seat. The depth of the seat is preferably made considerably shorter than it is usually constructed to enable the occupant to sit comfortably thereon without sliding forward to gain the necessary room for the bending of the leg at the knee joint. The front edge of the seat I propose to shape, as shown in Fig. 9, with a large downward curve, removing that part of the seat which ordinarily creates a pressure on the underside of the knee of the occupant.

The rear portion of the seat member 1 is formed with a deep bowl-shaped recess *r* as indicated in the sectional Figs. 7, 8 and 9; the forward portion of which cooperates with the forwardly disposed longitudinal hump *h* to form the relatively steep incline *e*. The incline *e* extends forwardly on either side of the hump *h* and forms two shallow channels *s* properly contoured to fit the thighs of the user. It, therefore, becomes apparent that by reason of the contour of the surfaces *r*, *e*, *h* and *s* on the seat member 1, a proper, accurate, form-fitting support is formed for the gluteofemoral muscles of the user.

The upright supports are preferably two in number for the reason to be hereinafter stated, but it will be understood that any number of supports may be employed without departing from the spirit of this invention. As shown in Fig. 2, the upright supporting members are shown in a fixed position with relation to the floor member 1 of the chair and extend upwardly with a gradual inclination toward the rear. As is customary in the design of many office chairs,

the back support is either pivoted at a point near the seat member or the seat itself mounted on a pivot so as to permit the user to rock backward whenever he wishes. This 5 feature of the usual office chair has the disadvantage of shifting the weight of the trunk of the body from the lower part of the pelvis to the spinal column and thus an incorrect habit of sitting posture results. The 10 above noted faults are corrected in the invention disclosed herein; the proper angle of inclination of the back support with respect to the chair seat remains always the same.

15 The supports 2 are separated sufficiently, as shown in Fig. 1, to allow ample room for the buttocks gluteal muscles, and thus it will be seen any person, whether of large or small build, may comfortably sit all the way back 20 in this type of chair and by so doing get the full benefit of the contour of the seat member and also of the back and shoulder rests.

At the upper end of the upright supporting member 2, it has been found desirable to 25 securely fix thereto a shoulder support 3 having the proper curves and shape, as indicated at *a* and *b*. The curve *a* is so designed as to afford a restful support for the shoulders 30 of the user while working without cramping or interfering with the normal movements of the scapulae or arms.

Between the shoulder support 3 and seat member 1, and within the plane of the upright supports 3, I mount a back supporting member 4 to support that part of the user's back known as the lumbar region. A critical 35 point in the design of posture chairs is the providing of an anatomically accurate support for this part of the back as it is in this region the worker tires first. As hereinbefore stated, supports have been made for this part of the back but have proved unsuccessful in that they were not adjustable to suit the back 40 of the user and did not cooperate with the form of seat to bring about the desired result.

The support 4 in this improved posture chair is mounted as at 5 so as to permit vertical adjustment thereof and also pivoted as 50 at 6 so as to move with the body and afford a resting support in all positions. As shown in the drawings, the adjustable feature consists of the notched plates 7 attached to the 55 upright supports and pivots 8 fixed to the member A. A recess 7^a is formed in each of the upright members 2 to provide clearance for the pivots 8 when moved into any of the notches 7^a formed in the plates 7. Obviously 60 other suitable means for mounting the cross member 4 so as to have a pivotal and vertical adjustment may be employed and therefore I do not limit myself to the precise construction shown in the drawings. An important 65 feature is that the seat is formed

to overcome any tendency of the body to slip forward, while the support 4 braces that part of the back especially needing support due to the position of the occupant brought about by the form of the seat.

It is also desirable to form the back rest member 4 with the forward surface curved in two planes, as indicated at *c* and *d*. The curve *d*, in the horizontal plane, more closely fits the contour of the user's back and thus affords a supporting surface for a greater area. The curve *c* in the vertical plane, more accurately fits the contour of the spinal column and due to its pivotal movement the member 4 readily adapts itself to fit the contour of the backs of a larger number of users. The dotted line positions shown in Fig. 10 serve to illustrate the pivotal movement of the back rest member 4, while the vertical adjustment thereof may be attained by moving the rest 4 forwardly out of one of the notches 7^a of the plates 7 and raising or lowering as desired, all of which may be quickly and easily done by the person while seated.

It therefore becomes apparent that all the important features of this type of chair cooperate together to bring about a correct posture sitting position and that the omission of one or more creates a deleterious effect on the user. For example, a recessed seat member without the proper support for the back and shoulders, and conversely, produces an injurious result, or the lack of ample room for the buttocks tends to cause a forward movement of the body and consequently the user sits in an incorrect and harmful position.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefor, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:

1. A posture chair comprising a saddle shaped seat member, upright members attached to the rear portion of said seat spaced the regulation distance apart, a shoulder rest fixedly mounted on the upper ends of said upright members and a relatively wide lumbar rest pivotally mounted on and between said uprights below said shoulder support, the parts being so proportioned that the two rests alone support the back of an occupant,

the said lumbar rest being of a shape and size to form a support for the lower part of the back of said occupant, whereby the lumbar rest will be tilted to different positions by contact of the occupant's back, the two contacting surfaces of the lumbar rest and shoulder rest with the back of the occupant being capable of being projected into different relative inclinations, one to the other, to enable the occupant's back to be supported in erect position at both the shoulders and at a point adjacent the base of the spine, while permitting the occupant to flex the portion adjacent the base of the spine into different postures in order to overcome the normal tendency to shift the buttocks, thereby maintaining the buttocks in proper position on the seat.

2. In a chair of the character described the combination of a seat with uprights projecting therefrom and spaced a substantial distance apart, said seat having a depression extending between the uprights, a hump formed on the forward part of said seat adjacent said depression, said hump being adapted to maintain the normal position of the buttocks within said depression, a fixed shoulder rest on said uprights, a lumbar rest pivotally mounted at a point adjacent the base of the spine and of a size and shape to afford a satisfactory support to the lower portion of the back of the occupant capable of being tilted by the occupant's back while the shoulders are pressed against the shoulder rest to change the inclination of the surfaces of the lumbar rest and the shoulder rest in their relation, one to the other, whereby the occupant's back will be properly supported both at the shoulders and near the base of the spine, said lumbar rest being automatically oscillated by any movement of the lower portion of the body, thereby permitting the occupant to flex the said portion of the body into different positions counteracting any tendency to shift the buttocks out of correct position within said depression.

In witness whereof, I have hereunto subscribed my name.

WILLIAM H. LEFFINGWELL.
